UNITED STATES PATENT OFFICE.

ANDREW CHURCH AND CHARLES A. CHURCH, OF ADRIAN, MICHIGAN.

FENCE-POST.

SPECIFICATION forming part of Letters Patent No. 780,638, dated January 24, 1905.

Application filed December 12, 1903. Serial No. 184,999.

To all whom it may concern:

Be it known that we, ANDREW CHURCH and CHARLES A. CHURCH, citizens of the United States, and residents of Adrian, in the county 5 of Lenawee and State of Michigan, have invented certain new and useful Improvements in Fence-Posts; and we do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 Our invention relates to improvements in the means commonly employed for strengthening or reinforcing fence-posts made from cement or concrete; and it has for its object to provide an article for this purpose that is so formed 20 from wire or other suitable material as to combine both internal strengthening means for the post and exteriorly-projecting eyes or loops to which a wire or other form of fence may be secured.

25 A further object of our invention is to provide a strengthening member of the class described that may be formed at the factory in compact form and packed in a small space for shipment to the place where the post is to be 30 made, at which time said member may be quickly and easily drawn out to the desired length, so that the projecting eyes may be spaced at desired distances apart before being placed into the post-mold to accommodate 35 the varying meshes of woven fences.

40 While the essential and characteristic features of our invention are necessarily susceptible of modification, the preferred embodiment thereof is illustrated in the accompanying drawings, in which—

45 Figure 1 is a vertical side elevation of a post embodying our invention. Fig. 2 is a detached view of the coil constituting a part of the complete post. Fig. 3 is a perspective view of a fence-post embodying our invention and showing a portion thereof broken away, and Fig. 4 is a plan view of the upper ends of the posts shown in Figs. 1 and 3.

Referring to the drawings, 1 represents an

ordinary fence-post made of cement or concrete and having longitudinally formed or embedded therein the strengthening wire or member 2, which as originally formed comprises a series of continuous elongated or elliptically-formed loops or coils, as shown in Figs. 2 and 5. After the member 2 has been formed into a coil the loops 3 thereof are expanded or separated at desired distances apart, as the meshes of the fence may require, and the said member is then in proper shape to be 60 embedded within the post when being formed.

A special feature in our invention is obtained by the coiling of the wires 2, as shown in Fig. 2, preparatory to its being expanded, inasmuch as the connecting portions of the 65 diagonally-disposed legs thereof form the transverse shoulders 4 within the post, the said shoulders acting as anchors for rigidly retaining in position each separated coil of the wire and also forming the eyes 5 exteriorly of the post, which provide means for securing a fence to such post.

It will be apparent that one or more of these reinforcing-coils may be used in the formation of a post of this class and that, if desired, 75 other strengthening means, such as the longitudinal strips 6, may be employed.

In the construction of cement posts we have employed reinforcing means of numerous shapes and styles and by reason of such experiments have ascertained that the strongest post and most satisfactory results can be attained by the use of a strengthening-strip substantially as herein described, which, in addition to its improved strengthening qualities, also combines the fence-retaining eyes 85 5, adapted to be spaced when the post is being made as the mesh of the fence to be strung may require.

On account of the weight of posts formed 90 from cement or other similar material it is found more convenient for the farmer or other person building the fence to have his own mold and make the posts as he may need them. By the use of the strengthening or reinforcing means herein described the manufacture 95 of posts at the place of use is made comparatively simple, as the coils of wire may be

formed at the factory and shipped in compact form to the user, who then expands them as the particular needs of his fence may require.

Having thus described our invention, what we claim as new, and desire to secure by Letters Patent, is—

1. In an article of the class described and in combination, a fence-post of plastic material and a single coil the convolutions of which are of elongated shape, said coil being stretched to provide a zigzag portion formed by the longer sides of the convolutions and connecting laterally-disposed portions provided by the ends of the convolutions, said coil being embedded within the post with corresponding untwisted ends of the convolutions projecting from one face thereof, the sides and laterally-extending portions of said ends coacting with said face of the post to provide eyes for the attachment of the fence fabric to the post, substantially as described.
2. In a plastic fence-post structure, the herein-described means for the attachment of

the fence fabric to the post, which consists of a coil of ductile material, the convolutions of said coil being of elongated shape and having laterally-extending ends providing shoulders, said coil being embedded in the post with the short untwisted sections of corresponding ends of the convolutions projecting from one face of the post to form attaching-eyes, and said coil being expansible lengthwise to varying degrees for spacing said attaching-eyes varying distances apart for the purpose of permitting different structures of fence fabric to be attached to the post, substantially as described.

In testimony whereof we have hereunto signed our names to this specification in the presence of two subscribing witnesses.

ANDREW CHURCH.
CHARLES A. CHURCH.
